UNITED STATES PATENT OFFICE.

CHARLES E. ZIMMERMANN, OF SYRACUSE, NEW YORK.

CUTTER-HEAD FOR MATCHING LUMBER.

SPECIFICATION forming part of Letters Patent No. 414,473, dated November 5, 1889.

Application filed February 4, 1889. Serial No. 298,566. (No model.)

To all whom it may concern:

Be it known that I, CHARLES E. ZIMMERMANN, of Syracuse, in the county of Onondaga, in the State of New York, have invented new and useful Improvements in Cutter-Heads for Matching Lumber, of which the following, taken in connection with the accompanying drawings, is a full, clear, and exact description.

10 This invention consists in the improved attachment of the cutters to the cutter-head, whereby said cutters are thoroughly braced, so as to prevent their being broken or allowed to tremble or be twisted out of line during 15 their operation.

The invention also consists in providing the cutter-head with screw-threaded sockets at opposite sides for the reception of the bolts by which the sustaining-sleeve is secured to 20 the cutter-head, and thus allowing the said sleeve to be attached to either side of the cutter-head and the latter to be adjusted for either right or left hand cutting, as may be desired, all as hereinafter more fully 25 described, and specifically set forth in the claims.

In the annexed drawings, Figure 1 is a top view of a cutter-head equipped with grooving-cutters. Fig. 2 is a side view of the 30 same, and Figs. 3 and 4 are detached plan and side views of a tonguing-cutter and its attachment to the cutter-head.

Similar letters of reference indicate corresponding parts.

35 A represents the rotary cutter-head, which is mounted usually on an upright arbor (not shown) and sustained thereon by the sleeve s, rigidly secured to the cutter-head and embracing the end of the arbor. By means of 40 a set-screw u, inserted in the upper end of the aforesaid sleeve and bearing on the end of the arbor, the cutter-head is sustained at the requisite distance from the work-table or bed of the machine to cut the tongue or groove 45 in the required position on the edge of the board.

To render the cutter-head reversible, so as to allow it to be operated to cut either right or left handed, I provide said cutter-head with 50 screw-threaded sockets a' a' a' in opposite sides and attach the sleeve by bolts i i i, pass-

ing through perforated ears s' s' on the sleeve and entering the sockets at the desired side of the head A. The head A is formed with laterally-projecting arms a a a, having straight 55 radial faces in planes parallel with the axis of the cutter-head. To said faces are attached the cutters C C C, which are curved slightly eccentrically in relation to the axis of the cutter-head and in a plane at right angles to 60 the said axis, and have integral with their heel ends attaching-shanks c c c, which project from the concave sides of the cutters and are secured to the radial faces of the arms a a a by means of bolts b b b, passing through 65 said shanks and arms. The arm a reaches beyond the junction of the shank c and cutter C, so as to form a bearing on the heel of the cutter, which bearing extends to a point in 70 range with the nearest outer face of the cutter. Said bearing braces the cutter so effectually as to prevent its trembling and breaking when in operation. At the same time the inner end of the cutter-shank c rests with a square face against the cutter-head, and thus 75 prevents the cutter from being twisted out of line. The free ends of the cutters are beveled on their inner sides to cutting-edges e e e on the exterior thereof.

The outer faces of the cutters C C C are 80 nearer to the axis of the cutter-head at the heels of the cutters than at the cutting ends thereof, for the purpose of affording proper clearance to prevent undue friction between the cutters and board operated on. In order 85 to sustain the cutters still more effectually in their operative position, the arms a a a may be provided with grooves l l l and the cutter-shanks c c c with tenons h h h, which enter said grooves.

For tonguing lumber I form the cutters with longitudinal grooves in their outer faces, which grooves are of a depth equal to the height of the tongue to be formed on the edge of the board. For grooving lumber I form 95 the cutters with longitudinal tongues t t t on their exteriors, said tongues extending beyond the cutting-edges of the portions of the cutters at opposite sides of the tongues, and the bevels on the inner sides of the cutters 100 are continued to the ends of the tongues to form the necessary cutting-edges thereon.

In order to provide for a proper clearance of said cutter-sections, I set them obliquely to the line of cutting, as shown in Fig. 5.

What I claim is—

- 5 1. The combination of the cutter-head A, formed with laterally-projecting arms *a a a*, having straight radial faces, and the cutters C C C, curved slightly eccentric in relation to the axis of the cutter-head and formed with the shanks *c c c*, and seated thereby on the radial faces of the aforesaid arms and braced by the ends of said shanks resting on the cutter-head, substantially as described and shown.
- 15 2. The combination of the cutter-head A, formed with laterally-projecting arms *a a a*, having straight radial faces, and the cutters C C C, curved slightly eccentric in relation to the axis of the cutter-head and

formed with the shanks *c c c*, and seated 20 thereby on the radial faces of the aforesaid arms and braced by the ends of the aforesaid arms bearing on the heels of the cutters at points in range with the nearest outer faces of the cutters, substantially as described and 25 shown.

3. The combination of the cutter-head provided with screw-threaded sockets *a' a' a'* at opposite sides, and the sleeve *s*, detachably secured to the cutter-head by bolts *i i i*, substantially as described and shown. 30

In testimony whereof I have hereunto signed my name this 2d day of February, 1889.

CHARLES E. ZIMMERMANN. [L. S.]
